ADDRESS PLATE

Walter T. Gollwitzer, Cleveland, Ohio, assignor
to Addressograph Company, Wilmington, Del.,
a corporation of Delaware

Application September 6, 1932, Serial No. 631,767

10 Claims. (Cl. 101—369)

This invention relates to a printing plate holder, and especially to a holder arranged to carry an embossed printing plate for use in printing addresses and the like.

The object of this invention is to provide a holder which will be so reinforced as to prevent the printing member carried by the holder from becoming warped or otherwise injured, due to rough handling, and at the same time provide a holder of sufficient size to accommodate not only the printing member, but also an indicia carrying card without sacrificing the rigidity of that portion of the holder which supports the printing member, while maintaining a minimum weight for the holder.

Other specific objects of the invention will become more apparent from the following description, which refers to a preferred form of holder illustrated in the accompanying drawing, and the novel features will be set forth in the claims.

In the drawing, Fig. 1 is a plan of a printing plate holder embodying my invention; Fig. 2 is a plan looking at the rear face of the holder illustrated in Fig. 1; Fig. 3 is an end view of the holder; Figs. 4, 5, and 6 are sections as indicated by the correspondingly numbered lines on Fig. 1; Fig. 7 is an end view of my improved holder, distorted by handling or other rough usage; Figs. 8 and 9 illustrate modified holders.

One use for printing plate holders, of the type with which my invention is concerned, is to print successive addresses or other data on successive envelopes or sheets. In such instances, a group of individual holders, each having its individual printing plate mounted thereon, are commonly stacked in a magazine, one on top of the other, and fed one at a time from the bottom of the stack to a printing mechanism, which makes the impression on the sheet or envelope by means of the printing member carried by the holder. The holders are then discharged into a receiving magazine, which in some instances is a filing drawer, in which a group of perhaps two hundred or more of such holders, together with their printing plates are stored. While this is the normal use of the holders, they are frequently sorted, and new holders substituted, to enable lists or addresses printed from the impression plates thereon to be maintained correct and up-to-date.

Further, many printing plates in the group or storage drawers may be used for a comparatively long period of time. Hence, to protect the printing plate during constant handling, the holder must be durable. Other plates in the group may be used a comparatively short time. For econ-

omy, the printing plates are removably secured in position on their respective holders, so that a new printing plate may be substituted for a discarded plate without causing the loss of the plate holder. It follows, therefore, that the holders are in use for comparatively long periods of time, and are constantly handled for the purpose of striking impressions therefrom, for maintaining the plates in proper order or sequence and for removing one printing plate from its holder and substitute a new plate in its place.

It has been found that metals are the most durable materials for use in manufacturing a holder and printing plate. However, as the holders may vary in size, some of them approximating four inches square, it can readily be seen that if they are to be stored in manually handled drawers or magazines containing possibly two hundred or more plate holders, it is highly desirable to eliminate all weight possible. Hence, sheet metal of relatively light weight is preferably used. It follows, therefore, that plate holders manufactured of such metal to be light must be reinforced for strength, to avoid distortion of the printing member, which in most instances also comprises a thin strip or plate of metal having the required printing character embossed thereon.

When the printing characters are embossed on metal plates it is exceedingly difficult for an operator to read them correctly. The color of the characters in such instances is substantially the same as the metal from which they are embossed or upstruck, and are ordinarily comparatively small, of a size such as typewriter characters. The embossed characters appear on the printing surface in reverse order and reverse position. Therefore, in order to read the character the operator must read from right to left, rather than from left to right, as the ordinary printing. In view of these difficulties, it has been found desirable to removably mount on the holder a card having printed thereon such data as will identify the printing plate carried by its holder. For this purpose, the use of a white or light-colored card is preferred, as such a card may be printed in black or other contrasting color in the regular manner. However, the use of such cards materially increases the size of the holder, usually doubling it.

In ordinary printing machines, used to make impressions from the printing plate carried by such plate holders, the holders are supported during the printing operation over the entire region below the printing plates by a suitable anvil,

and are either struck by a reciprocating platen member, or a platen roller is drawn across the plates. Both of these methods, and mechanisms to accomplish them, are well known in the art. 5 However, in either type of mechanism the paper is disposed between the platen and the printing plate. Hence, if the printing plate is not flat, a distorted impression will result. This is especially true in cases where the plate has a ridge formed 10 thereon, due to the bending of the holder and its plate by rough handling.

It is therefore apparent that to obtain the best results, the holders must be made as rigid as possible to prevent the distortion of the printing 15 plates, and they likewise must be made as light as possible to permit them to be stored in magazines containing a comparatively great number of plates without causing the magazine to be of such weight that it cannot be easily handled by 20 the operator.

Referring now to the drawing, 10 indicates in general an address plate holder embodying my invention. Removably mounted on the holder 10 is a printing member 11 and an identification 25 or data card 12. The holder 11, for reasons herefore explained, preferably comprises a flat, comparatively light metal plate, approximately ten to fifteen thousandths of an inch in thickness.

30 The printing plate may be, as shown, a thin metallic plate or strip of substantially the same material as the holder and having embossed thereon suitable printing characters 15. The length of the printing strip is approximately the 35 same as the length of the holder and the height materially less, in order that a sufficient amount of holder surface may be provided to support the indicia card.

As shown in Fig. 1, the printing plate 11 is 40 movably secured in position on the lower portion or area 16 of the holder. The lowermost edge of the holder is bent upwardly and inwardly on itself forming a lip 17 extending across substantially the entire lower edge of the holder 45 and beneath which lip the printing plate may be slid to position it on the holder. The upper edge of the printing plate is positioned by a series of lips 18, which are struck up from the body of the plate and then bent downwardly parallel to the 50 surface of the holder to overlie the upper edge of the printing plate. The printing plate is prevented from endwise movement by abutments 19 carried by tongues 20 which are separated from the holder on three sides in order that they may 55 be depressed to enable the printing plate to be slid over the abutments for the purpose of placing it on, or removing it from, the holder.

The identification or data bearing card 12 is 60 removably secured to the top portion or area 21 of the holder. This card is preferably paper or cardboard and has sufficient rigidity to enable it to be retained in place on the holder in such a manner as will permit the greater portion of the card to be visible to the operator. As shown 65 in Figs. 1 and 4 the upper edge of the card 12 underlies a lip 22 bent upwardly and downwardly parallel with the body of the holder, while the lower edge of the card is retained by a series of lips 23 struck up from the plane of the holder 70 and overlying the bottom edge of the card.

The card 11 is prevented from shifting sideways of the holder by a corner lip 23a and a lip 24, both of which are struck up from the holder 75 and overlying the left hand edge of the card in

a manner similar to the lips 23. An abutment 25 struck up from the holder prevents the card from movement toward the right (Fig. 1). The cards are preferably flexible and therefore may be readily raised above the abutment 25 for removal or insertion on the holder. 5

From the foregoing it is readily seen that the lips 17 and 22 which aid in retaining the plate 11 and card 12, respectively, in place on the holder, together with the lips 23 and 18 serve 10 to materially strengthen the holder against bending in a direction transversely of the card and printing plate. However, they do not aid in preventing the bending of the plate and holder along lines parallel or substantially parallel with 15 the long dimension of the printing plate or card. In the past, the sides of the holder have been bent inwardly upon the back of the holder for its entire height. This bent part was then upset between its inner and the outer edges and 20 squeezed together to form a spacing flange. The flanges were, however, designed to space the plate holders so that when they were stacked flat, one on top of another, the bottom of one holder would not rub or mar the impression surfaces of the 25 printing plate carried by the holder directly below. Such a holder is shown in Patents 1,096,495, and 1,812,894, issued to Addressograph Company, as assignee of J. S. Duncan, May 12th, 1914, and V. J. Mohler, July 7, 1931, respectively. 30

The side ribs described, while designed to space the holders would, of course, serve to strengthen them against bending along lines passing through the ends of the holder. However, I have found that the most severe strains to which 35 the holders are subjected, act in such a direction that the plates are bent longitudinally of the printing plate. I have also found that when the entire length of the ends of the holders are flanged as just described, that unless considerable 40 material is used in making the flanges, (that is, unless the rib has considerable depth and its base considerable width), such construction does not prevent the holder from being bent along a longitudinal line, with the result that the plate 45 is distorted and defective impressions are made, as heretofore explained. Other formations of reinforcing beads have been tried with the same results.

When end reinforcing members are used which 50 have sufficient strength to resist the forces which cause the bending of the holder, either the size or weight of the holder is increased an amount which presents a serious obstacle in the handling of a drawer or magazine containing a number of 55 holders. When the depth of the reinforcing flange is increased to strengthen the holders, the number of such holders which can be stacked, one on top of the other, in a definite height, is decreased, thereby requiring more frequent changing of 60 magazines and requiring additional storage space. Either of these conditions presents serious disadvantages in handling the printing plate holders in actual use. 65

Due to present demands for greater printing area, the size of the holders are constantly being enlarged. That is, the distance from top to bottom is being increased. Such enlarged holders are much more easily bent than their predecessors, and the disadvantages of former constructions is increased and the problem of strengthening such enlarged holders to overcome the disadvantages made more difficult. Likewise, in recent 70 years, the art of printing from address plates has 75

advanced materially and the demand for more accurate copy has increased with this advancement. Hence, defects in impressions, which before were considered immaterial, have now become highly material.

It is obvious that to strengthen the edge of the holder or increase the weight or size of the material, while it might overcome the lack of rigidity of the holder, would present other disadvantages which are highly undesirable. However, I have found that by decreasing the amount of reinforcing at the ends of the holder I can increase the rigidity of that portion of the holder which supports the printing plate, and it is the bending of such portion or area that affects the impression. Likewise, not only am I able to increase the rigidity of the portion of the holder which supports the impression plate, but at the same time I decrease the amount of metal in the holder thereby by decreasing its weight as well as the weight of a magazine containing, for instance, two hundred such holders.

To accomplish the result just described, I employ reinforcing ribs of substantially the same cross-section as used in the past, but I extend such reinforcing along the ends of the holder from the bottom edge thereof for a predetermined distance, which in all instances be less the length of the end of the holder, and preferably will be a distance substantially equivalent to the end of the area 16 of the holder, over which area is superimposed the printing plate 11. The remaining portion of the edge is turned or bent upwardly and inwardly parallel and contacting with the surface of the holder, which prevents possible contact by the operator with sharp edges of the holder.

My improved address plate holder is reinforced at its ends by ribs 32 which extend upwardly on the underside of the holder for a distance less than the total length of the holder. Preferably the ribs are substantially the same length as the height of the maximum sized printing plate used.

As shown in Figs. 2 and 5, the sides or ends 39 of the holder are not continuous, but are interrupted by a shoulder 31, the lower or ribbed portion of the sides extending outwardly beyond the upper or nonribbed portion of the sides. As shown, the lower portion of each side is bent downwardly and inwardly forming a flange 32, which abuts the underside of the holder. Intermediate the inner edge 33 of each flange 32 and the edge 34 of the holder, the flange is upset and formed into downwardly extending corrugation or rib 35, which reinforces the holder at the ends of the area 16 which supports the printing plate.

By constructing my holder in this manner, I have shortened the length of the reinforcing beam or beam. It follows, therefore, that I have increased the rigidity of the beam without adding material or changing the cross-sectional dimension of such reinforcing from that which has been in use heretofore. This, therefore, increases the rigidity of that portion of the holder which supports the printing plate.

Address plate holders are used, as heretofore mentioned, in printing machines which automatically feed a holder at a time, from the bottom of a stack of holders retained in a vertically extending magazine, across a table to an impression position. As a rule, the holders are fed by bars or chains which are provided, at predetermined intervals, with upstanding lugs arranged

to engage the rearmost edge of a holder and shove it forward. Generally such lugs engage a reinforcing member of the holder. In my improved holder, the reinforcing ribs do not extend to the rearmost edge of the plate, hence I cut back the edges of the holder above the reinforcing member as at 41 to a point beyond the reinforcing rib 35, and thereby provide an abutment 31 against which the feeding lugs may strike.

Again the shortening of the reinforcing rib is highly advantageous. Heretofore when the reinforcing rib extended the entire length of the plate and a plate was jammed or its progress in the printing machine was inadvertently blocked, the feeding lug sometimes buckled the reinforcing rib. However, by shortening the rib I have increased its rigidity as a column and decreased the tendency of the holder to become distorted due to the action of the feeding lug on the reinforcing rib when the holder is inadvertently jammed in the magazine or raceway of the printing machine.

Present day requirements include the use of printing plates having a varying number of printing lines and to eliminate excess weight, the height of the plate is varied as desired. Figs. 1 to 7 illustrate a holder having plate of maximum height, while Figs. 8 and 9 illustrate a holder having printing plates of less than maximum heights. The scale of Figs. 8 and 9 is half the scale of Figs. 1 and 2.

Fig. 8 illustrates a holder 10A of the same outside dimensions as Fig. 1, but having a printing plate 11A, the height of which is less than the height of the printing plate 11 of Fig. 1. In this instance, the height of the data or index card 12A is considerably greater than the height of the card 12 in Fig. 1. Such a card provides space in which the operator may make various notations such as credit, purchasing statistics, or dates of payments, etc.

In Fig. 9, I illustrate a holder 10B for use with a printing plate 11A, but arranged to accommodate a smaller index card 12B. Such holders are used where but little data is to be carried by the index card and where it is desired to eliminate all excess weight and reduce the cost and size of the holder.

It will be noted that the reinforcing rib of the holders of Figs. 1, 8, and 9 are all the same length and the variation in height of the holder is compensated for by varying the height of the cut-away portion 40 of the holder. Such construction enables holders carrying different width of index cards, printing plates or both to be conveniently utilized in the same printing machine without any change of the feeding mechanism, or to be interspersed with the wider plates in the magazine of the printing machine. Moreover, when the address plate holders are filed in the drawer, they may be retained thereby by cleats on the low sides overhanging the tops of the ribs on the holders, and herein my invention is useful in allowing the same drawer to lock within it, address plate holders having the card carrying portions, the plate carrying portions or both portions of varying heights.

Certain types of addressing machines are equipped with standard size platens arranged to print from maximum sized printing plates. In order that the distortion or bending of the holder will not cause the index card or its retaining lips to coact with the platen, it is therefore desirable that the holder be reinforced over the entire region over which the plate is superimposed.

- This is especially true where various types of holders such as are illustrated in Figs. 1, 8, and 9 are dispersed in the same magazine. I therefore find that the most advantageous length reinforcing rib is one substantially as long as the width of the maximum sized printing plate to be used. It will be noted that the reinforcing ribs of all types of plate illustrated are of the same length.
- 10 It will be noticed that by constructing the holder as above described, I have appreciably decreased the rigidity of that portion or area which supports the index card. This, however, is not a disadvantage, but rather an advantage, since by 15 decreasing the rigidity or weakening the area of the plate which supports the index card, distortion resulting from rough or careless handling or use will be localized to that area.
- In addition to localizing the area of distortion, 20 I have decreased the amount of metal used in manufacturing these plates. While the amount of this decrease is small, it is, as heretofore pointed out, important as it permits three to four percent more plates (of the size shown in the 25 drawing) to be stored in a magazine or filing drawer without increasing the weight of such magazine. Reference is made to my copending application No. 748,705, filed October 17, 1934, for claims on a system of printing comprising a 30 method and apparatus for employing the articles described and claimed in this application.
- I claim:
1. An address-printing device, having an area provided with a printing medium, an extension of 35 the device above the printing medium for carrying an index card, reinforcing ribs extending across the ends of the printing plate area, but terminating below the top of the device, said ribs being continuous throughout their entire length.
  - 40 2. An address plate holder having an area provided with retaining devices about the margin thereof for holding a printing plate on the holder, an extension of the holder above the printing plate area for carrying an index card, and reinforcing 45 ribs at the ends of the printing plate area which extend continuously across the entire printing plate area and terminate a substantial distance below the top of the holder.
  - 50 3. An address plate holder having an area provided with a bead about the lower margin thereof and retaining devices adjacent its upper margin, for holding a printing plate on the holder, an extension of the holder above the printing plate area, a bead along the upper edge of said extension and retaining devices along the lower edge thereof, for holding an index card on the extension and reinforcing ribs at the ends of the printing plate area, which terminate approximately at the 55 top and bottom of the plate area and extend continuously throughout their length to reinforce such area.
  - 60 4. A holder for a printing plate and an index card, comprising a member having a lower area equipped with marginal means for holding a 65 printing plate thereon, an upper extension of the holder of less length than the lower region being inwardly offset therefrom at each end and provided with means for carrying an index card, the wide and narrow portions of the one-piece frame 70 corresponding approximately to the lengths of the

plate and card respectively and ribs formed on the projecting portion of the lower region at each end thereof and extending continuously from the top to the bottom of the lower region.

5. A holder for a printing plate and an index 5 card comprising a member having a lower area equipped with means for holding a printing plate thereon, an upper extension of the holder of less length than the lower region being inwardly offset therefrom at each end and provided with means 10 for carrying an index card, the lower edge of which is carried by means on the lower area, the wide and narrow portions of the one-piece frame corresponding approximately to the lengths of the plate and card respectively and ribs formed on the 15 projecting portion of the lower region at each end thereof, and extending continuously from the top to the bottom of the lower region.

6. An address plate holder having a portion of its opposite sides extending outwardly beyond the 20 remaining portions, reinforcing ribs underlying such extensions, and retaining devices on the holder to support a printing device on that area of the plate bordered by said extensions.

7. An address plate holder having a lower portion 25 projecting outwardly at each end beyond the upper portion, reinforcing ribs underlying such projecting portions and extending continuously from top to bottom thereof, and retaining devices 30 on the holder to support a printing device on the lower area of the holder between said extensions, and to hold an index card on the upper portion, the wide and narrow portions of the one-piece frame corresponding approximately to the lengths 35 of the plate and card respectively.

8. An address plate holder comprising a thin metallic plate, reinforcing members at opposite ends of said holder and extending from the bottom thereof a predetermined distance and terminating short of the top of the holder, and means 40 on said holder to support a printing device on the area reenforced by said reinforcing members, whereby the lower region of said holder is made more rigid than the upper region so that the tendency of the holder to distort will be localized to the 45 upper region.

9. An address plate holder comprising a single integral member having a lower portion extending at each end beyond the remaining upper portion, retaining devices on said holder for holding 50 a printing plate on the lower portion, reinforcing ribs underlying the extensions of the lower portion and extending continuously from one end of the lower portion to the other, and means for engaging the ends of an index card overlying the 55 upper portion, arranged to hold a card which does not extend beyond the ends of the upper portion.

10. An address plate holder having a lower portion and an upper portion integral therewith, the lower portion being longer in opposite directions than the upper portion, reinforcing hollow ribs on the back of the extensions of the lower portion, the upper portion being bent at its ends substantially flat against the plate to protect such ends 65 without stiffening them to the extent of the lower portion, means for holding a printing plate entirely between the ribs, and means for holding an index card in position to overlie the upper portion.

WALTER T. GOLLWITZER. 70
